(57) **CLAIM**

The ornamental design for a linear actuator body, as shown and described.

DESCRIPTION

FIG. 1 is a left side/rear/top isometric view of a linear actuator body of my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a front elevational view thereof.

It being understood that the material shown in broken lines is for illustrative purposes only and forms no part of the claimed design.
